UNITED STATES PATENT OFFICE.

NIC KRUMP, OF CHICAGO, ILLINOIS.

BENDING MACHINE FOR ANGLE IRONS.

Application filed December 23, 1922. Serial No. 608,640.

To all whom it may concern:

Be it known that I, NIC KRUMP, a citizen of the United States, and a resident of Chicago, in the county of Cook and State 5 of Illinois, have invented certain new and useful Improvements in a Bending Machine for Angle Irons, of which the following, when taken in connection with the drawings accompanying and forming a part hereof, 10 is a specification.

This invention relates to a machine for bending angle irons or bars into a circular form, for use in making tanks, and other articles.

15 Among the objects of the invention are to obtain a bending machine by means of which an angle iron or bar may be bent into circular form, and an angle iron of a different size and thickness than said first named 20 angle iron may also be bent into circular form by an adjustment of the co-acting bending rolls of the machine; to obtain means to readily and accurately adjust said rolls and to maintain them in an adjusted position, 25 both vertically and horizontally; and to obtain a bending machine which is simple in construction, easily operated, durable, and not liable to break or get out of order.

In the drawings referred to Fig. 1 is a 30 top plan view of a machine embodying the invention.

Fig. 2 is an end elevation of said machine.

Fig. 3 is a vertical section on line 3—3 of Fig. 1, viewed as indicated by arrows.

35 Fig. 4 is a vertical section on line 4—4 of Fig. 1 viewed as indicated by arrows.

Fig. 5 is a vertical section on line 5—5 of Fig. 1, viewed as indicated by arrows.

A reference character applied to designate 40 a given part indicates said part throughout the several figures of the drawings wherever the same appears.

A represents the table of the machine, and a, a, the upper ends of legs supporting 45 the table. C represents a vertical shaft which is rotatably mounted in journal bearing D. E represents a collar which is rigidly secured on shaft C by set nut e. F represents a roll which is mounted on shaft C 50 to be vertically adjustable, and to turn therewith. The periphery of roll F is provided with corrugations, (Fig. 2), and said roll acts as a driving roll, to force the angle iron or angle bar (X) which is to be curved. 55 through the machine. f'', f'' represents nuts which are set against each other on bolt f.

F' represents a plate which is secured on the upper side of roll F by the screws f', f'. F'' represents a washer loosely mounted on bolt f. f''' represents a bolt which extends 60 through bolt f and is enlarged at its lower end. The bolt f is split at its lower end, so that it is held in an adjusted position in shaft C when the bolt f''' is drawn upward to set the lower enlarged end thereof in the 65 split part of bolt f. F''', F''', represent nuts which are set against each other to lock bolt f''' in position when said bolt is drawn upward as above recited. f'''' represents the hexagon upper end or head of 70 bolt f. To adjust roll F vertically on shaft C, nuts F''', F''', are loosened and bolt f''' is driven down to release bolt f, and said bolt f is turned by placing a wrench on head f'''' thereof, thus raising or lowering 75 the roll F, as required; said roll resting on the locked nuts f'', f'' and supported thereby. After said roll F is adjusted it is locked in position by turning the lower one of nuts F''' to bring the enlarged lower end 80 of bolt f''' firmly into the split lower end of bolt f, and the upper one of said nuts F''' is then set firmly against the lower one to lock said bolt f''' in place. The vertical 85 adjustment of roll F is determined by the thickness of the horizontal flange of the angle iron (or bar) which is being forced through the machine, when the bend desired requires said flange to be underneath said roll: and said roll is adjusted so that the 90 lower end thereof is close to table A, when the bend desired requires said horizontal flange to be underneath the hereinafter described rolls.

G represents a worm gear wheel which 95 is rigidly mounted on shaft C, and H represents a driving shaft having worm h mounted thereon to engage with said worm wheel G. h', h', represent the journal bearings of shaft H, and said bearings 100 are secured to the under side of table A. I, J, K, respectively represent rolls arranged to co-act with roll F, in the operation of the machine. Rolls I, J, K, are respectively mounted on shafts i, j, k. Rolls I and J are 105 vertically adjustable on shafts i, j, in the same manner as roll F is adjusted on shaft C, and for the same reasons assigned for the adjustment of said roll F. Shaft i is rigidly mounted in table A, and shaft j is 110 rigidly mounted in frame j'. Frame j' is movably mounted in slot or aperture L pro-

vided therefor in table A. Shaft k is rigidly mounted in frame k' , and said frame is movably mounted in slot L' provided therefor in table A. L'' is a slot under slot 5 L' , but is not so wide as is said slot L' . m'' represents a bolt by means of which the frame k' is forced forward into an adjusted position in slot L' ; and said frame, after being adjusted as recited, is rigidly held in 10 its adjusted position by the block l , bolt K and nut K'' . M represents a spring one end of which abuts against frame j' , and the other end against plate m . m' represents a bolt by means of which plate m is 15 forced against spring M to control the tension thereof. Roll J is yieldingly held against angle iron X by said spring M .

Roll K is adjusted vertically on frame k' , by loosening set screw k''' and raising shaft 20 k , and when the adjustment is made said set screw is again tightened in collar k'' to secure the collar in place on shaft k . In case the horizontal member of the angle iron which is being bent is to be on the inside 25 of the curve obtained the lower end of roll K is close to contact with the upper face of the table A, and in case said horizontal member is on the outside of said curve it is raised so as to be in close contact with 30 said horizontal member.

The function of roll I , when an angle iron or bar is being forced through the machine, is to hold said iron or bar in proper position, and the function of roll J at said 35 time is to hold said iron or bar against roll F , so that said roll F will force the iron or bar which is to be curved through the machine.

N represents a roll which is rotatably 40 mounted in frame n , with its shaft or axle in a horizontal plane, said frame being positioned in recess N' in table A, and vertically movable, to correspond with the thickness of the horizontal member of the angle 45 iron or bar which is being forced through the machine. O represents a wedge which extends underneath frame n , the under face of said frame corresponding with the upper face of said wedge, to maintain the shaft 50 or axle of roll N in a horizontal plane. O' represents a bolt which is illustrated as provided with groove O'' . P represents a pin positioned in said groove and driven into vertical member p at one end of wedge O , 55 and illustrated as integral therewith. The turning of bolt O' moves the wedge O , to raise or lower frame n , as required, to correspond with the thickness of the horizontal member of the angle iron or bar which is 60 being curved.

Q , R , respectively represent eccentric 65 rolls, which are rigidly mounted on shafts or axles q , r , and q' , r' , represent handles or levers which are secured in said shafts or axles and by means of which said eccen-

trics are forced against the angle iron or bar (X), as said iron or bar is being forced through the machine. The function of these eccentrics is to prevent "squirming", as it is called, of the angle iron or bar as it is 70 being bent or curved in the machine. When the horizontal member of said angle iron or bar is on the outside of the circle or hoop which is being made one of said eccentrics is forced against the vertical member of said iron or bar, and when said horizontal member is on the inside of said circle or hoop the other of said eccentrics is forced against said vertical member. 75

The rolls F , I , J , K and N being properly 80 adjusted for a given angle iron or bar, to operate the machine said iron or bar is forced between rolls F and J , and shaft H is rotated, thereby turning roll F , and said iron or bar is thereby forced forward to and 85 beyond roll K , and is thereby curved, the amount of said curve being determined by the adjustment of said roll K , relative to roll F .

I claim:

1. In a machine for bending angle iron, a plurality of vertical shafts, one thereof a driving shaft, and a plurality of rolls mounted on said shafts, in combination with means to vertically adjust said rolls, said means comprising a screw threaded hole in the upper ends of said shafts, bolts provided with corresponding screw threads fitting said screw threaded holes, means to suspend said rolls on said bolts and means to secure said bolts in a determined position. 90

2. In a machine for bending angle iron, a plurality of vertical shafts, one thereof a driving shaft and one rigidly mounted in spaced relation to said driving shaft, and the remainder movably mounted to be in adjustable spaced relation to said driving shaft, and a plurality of rolls mounted on said shafts, the roll on said driving shaft mounted thereon to turn therewith, in combination with means to vertically adjust said rolls on said shafts, said means comprising screw threaded holes in the upper ends of shafts, bolts provided with corresponding screw threads to fit said holes, nuts locked together 105 on said bolts, plates on said bolts resting on said nuts, and means to secure said plates to said rolls, and means to secure said bolts in an adjusted position. 110

3. In a machine for bending angle iron forced therethrough, a table, a corrugated roll, the lower end thereof in spaced relation to said table and a rotatably mounted vertical shaft, said roll rigidly secured on said shaft, a worm gear wheel below said table rigidly secured on said shaft, an additional shaft rotatably mounted and a worm on said additional shaft arranged to intermesh with said worm gear, in combination with a roll rotatably mounted in a frame positioned 120 125 130

- in a recess in said table, means to adjust said frame vertically to maintain said roll in determined spaced relation to said lower end of said first named roll, an additional roll 5 mounted on a vertical shaft and means to yieldingly hold said additional roll in spaced relation to said first named roll, means to adjust the tension of said means to yieldingly hold said roll, another and additional roll 10 mounted on a rotatable vertical shaft, and adjustable means to maintain said last named roll in determined spaced relation to said first named roll, a roll mounted on a rigidly positioned shaft, also in spaced relation to 15 said first named roll, and eccentrics mounted on horizontal shafts, with means to force said eccentrics into contact with said angle iron which is being forced through the machine.
4. In a machine for bending angle iron 20 forced therethrough, a table, a corrugated roll, the lower end thereof in spaced relation to said table, a rotatably mounted vertical shaft, said roll rigidly secured on said shaft, a worm gear wheel below said table rigidly 25 secured on said shaft, an additional shaft rotatably mounted below said table and a worm on said additional shaft arranged to intermesh with said worm gear, in combination with a plurality of additional rolls, one of
- 30
35
40
45
50
- said additional rolls rotatably mounted on a rigidly held vertical shaft, another of said additional rolls mounted on a vertical shaft which is movably mounted and means to yieldingly hold said last named roll in spaced relation to said first named roll, and the remaining one of said additional rolls rotatably mounted on an adjustably movably mounted shaft, means to adjust and maintain said last named shaft to hold said last named roll in a determined spaced relation to said first named roll, said table provided with recesses, a vertically movable frame in one of said recesses, a roll rotatably mounted in said last named frame, and means to adjust and maintain said frame to hold said roll therein in determined spaced relation to the lower end of said first named roll, and eccentrics, one thereof mounted above said table and the other in one of said recesses in said table, and handles to said eccentrics whereby they may be forced against an angle iron which is being forced through the machine.

NIC KRUMP.
